(57) **CLAIM**

The ornamental design for a part of a forklift truck, as shown and described.

DESCRIPTION

FIG. 1 is a back perspective view of a part of a forklift truck, according to the inventors;

FIG. 2 is a bottom view of the part of a forklift truck illustrated in FIG. 1;

FIG. 3 is a front view of the part of a forklift truck illustrated in FIG. 1;

FIG. 4 is an inside view of the part of a forklift truck illustrated in FIG. 1;

FIG. 5 is a back view of the part of a forklift truck illustrated in FIG. 1;

FIG. 6 is an outside view of the part of a forklift truck illustrated in FIG. 1; and,

FIG. 7 is a top view of the part of a forklift truck illustrated in FIG. 1.

The broken lines shown in the drawings illustrate portions of the part of a forklift truck that form no part of the claimed design.
